CHAMPAGNE GLASS OR SIMILAR ARTICLE

George L. Traner, Barrington, Ill., and Don A. Schreckengost, East Liverpool, Ohio, assignors to Royalon, Inc., Sebring, Ohio, a corporation of Ohio

Filed Apr. 6, 1964, Ser. No. 79,356

Term of patent 14 years

(Cl. D36—8)

FIG. 1 is an elevational view of a champagne glass or similar article, showing our new design;

FIG. 2 is a bottom view thereof;

FIG. 3 is an enlarged detail view in elevation of one of the facets and the surrounding surface of this design, and

FIG. 4 is an enlarged sectional view taken along line 4—4 of FIG. 1.

We claim:

The ornamental design for a champagne glass or similar article, substantially as shown.
